UNITED STATES PATENT OFFICE

HOWARD E. FRITZ, OF AKRON, OHIO, ASSIGNOR TO THE B. F. GOODRICH COMPANY, OF NEW YORK, N. Y., A CORPORATION OF NEW YORK

CUSHIONING ANCHORAGE DEVICE

Application filed July 26, 1928. Serial No. 295,452.

This invention relates to containers, such as tank cars, for example, and especially to lined tank cars having well-pipes therein for use in filling or emptying them of their contents.

A defect of such tank cars as heretofore constructed has been that the well-pipe has not been suitably anchored or supported at its lower end to prevent it from being broken by strains imposed upon it in the travel of the car, and this defect has been especially serious in the case of tank cars lined with rubber or other chemical-resisting material because of damage to the expensive lining resulting from contact of broken portions of the well-pipe or its mounting.

One of my chief objects is to correct this defect and thus to provide for the use of well-pipes in tank cars or the like without the usual danger of breakage of the pipe or damage to the inner surface or lining of the car. Another object is to avoid abrasion of the rubber covering on the well-pipe. A further object is to provide a resilient anchorage for an end of the well-pipe whereby the latter holds said anchorage in fixed position.

In the preferred form of my invention I attain these objects by providing resilient means for supporting the pipe and especially a resilient anchorage for the lower portion of the pipe so as to permit limited but cushioned movement of its lower end and thus avoid breakage notwithstanding distortion and swaying of the car in service.

35 Of the accompanying drawings:

Fig. 1 is a side elevation of a tank car embodying my invention in its preferred form.

Fig. 2 is a vertical section on the line 2—2 of Fig. 1.

40 Fig. 3 is a vertical section on the line 3—3 of Fig. 1.

In the drawing, 10 is a railway tank car, and 11 is a rubber-lined tank mounted thereon and having the usual dome portion 12 located 45 in a central region on the top thereof, and having its bottom provided with a generally hemispherical sump 13 directly below the dome 12. The sump has a rubber lining 14 somewhat thicker than the rubber lining of 50 the other portions of the tank.

The dome 12 is formed with a circumferential restricted zone 15 near its top, and a rubber-lined pipe or the like 16 opens into the dome at said restricted zone, the pipe 16 normally being closed by a flanged plate or the like 17. The marginal portion of the restricted zone of the dome 12 is flared radially and forms a flange upon which a rubber-covered, centrally apertured, closure member 18 is mounted, said closure member being secured by a plurality of bolts 19. The closure member 18 has its central portion dished or depressed as at 20, and the central aperture therein is designated 21.

Extending downwardly through the aperture 21 is a cylindrical well-pipe 22 which has its inner and outer surfaces covered with rubber. The upper end of the well-pipe 22 is threaded into a rubber-covered flanged collar 23 the flange of which extends over and is secured to the closure member 18 by stud-bolts 24 and nuts 25, the stud-bolts being threaded into the member 18 and passing freely through suitable bolt-holes in the collar-flange.

75 A flanged cap or plate 26 of rubber-covered metal is secured against the top face of the collar 23 by the stud-bolts 24 and nuts 27. The cap 26 provides a closure for the upper end of the well-pipe 22, and is easily removed for the filling or emptying of the tank without disturbing the well-pipe support.

75 A flat cover-plate 28 is hinged at 29 in a pair of ears 30 rising from the closure member 18, and affords protection to the exposed rubber surfaces of said closure member and the cap 26 to prevent deterioration of the rubber from exposure to the elements.

For supporting and anchoring the well-pipe 22 at its lower end, a removable substantially-hemispherical pipe support 31 of cushioning material, preferably of a resilient material such as rubber, is provided, the said support being in the form of a plug of 90 rubber shaped to fit into and fill the sump 13 to a point nearly flush with the bottom of the tank.

95 The pipe support 31 is formed with an axial bore 32 extending from its top surface 100

downward for a substantial distance, the said bore 32 being adapted to receive the lower end of the well-pipe 22. In continuation of the bore 32 is a coaxial bore 33 of 5 smaller diameter extending downwardly to a point somewhat above the bottom of the pipe support 31. At the juncture of the coaxial bores 32 and 33 is a lipped flange or shoulder 34 adapted to engage the inner surface of the end of the well-pipe 22 and thus 10 to effect the firm seating of the latter.

The axial bore 33 communicates at its 15 lower end with a plurality of arcuate passages 35, 35 which are formed in the pipe support 31 and extend respectively to the upper surface thereof, the combined capacity of the several passages 35 being substantially the same as the capacity of the bore 33.

The invention provides two-point support 20 for the rubber-covered well-pipes in rubber-lined tank cars, and the yielding character of the lower support insures against abrasion of the rubber covering on the well pipe.

This embodiment of the invention in no 25 way interferes with the filling or emptying of the tank, which is accomplished in the usual manner through the well-pipe. Being located at the lowest point of the tank, the pipe support 31 permits the tank to be completely drained. The pipe support is easily 30 removable from its position in the sump for cleaning or replacement after the well-pipe 22 is removed, said well-pipe at other times holding the support firmly within the sump.

35 The use of my invention permits the attainment of the advantages set forth in the statement of objects, and it provides a simple, secure, resilient and easily renewable anchorage for the well-pipes of rubber-lined 40 mobile tanks or tank cars whereby breakage of the well-pipes and resulting injury to the inner surface of the tanks due to such breakage is avoided.

45 My invention is susceptible of modification within the scope of the appended claims.

I claim:

1. In combination, a mobile tank formed with a sump, a resilient member comprising a rubber mounted in said sump, and a well-pipe 50 mounted in said tank having its lower end engaged with said resilient member and holding the same firmly within the sump.

55 2. In combination, a mobile tank formed with a sump, a cushioning member mounted in said sump and formed with a recess in its upper face, and a well-pipe mounted in said tank having its lower end removably seated in said recess whereby the cushioning member is held in fixed position within the sump.

60 3. A combination as defined in claim 2 in which the cushioning member is formed with a passage communicating with said recess and the interior of the tank.

65 4. In combination, a mobile tank formed

with a sump, a rubber block removably mounted in the sump and formed to engage a well pipe and cushion the same, and a well pipe suspended in said tank and engaging said block.

70 5. In combination a mobile tank formed with a rubber lined sump, a block resiliently supported in said sump and formed to engage a well pipe, and a well pipe engaging said block and suspended from the top of 75 said tank.

6. A resilient support adapted to be used in cushioning a well pipe suspended in a mobile tank, said support comprising a body of rubber formed to removably engage a sump in the tank and to engage the well pipe.

80 7. A device as defined in claim 6 in which a passage for fluid is provided to connect the interior of the tank with the interior of the well pipe.

85 In witness whereof I have hereunto set my hand this 16th day of July, 1928.

HOWARD E. FRITZ.

CERTIFICATE OF CORRECTION.

Patent No. 1,784,897.

Granted December 16, 1930, to

HOWARD E. FRITZ.

It is hereby certified that error appears in the printed specification of the above numbered patent requiring correction as follows: Page 2, line 49, after the word "rubber" insert the word cushion; and that the said Letters Patent should be read with this correction therein that the same may conform to the record of the case in the Patent Office.

Signed and sealed this 22nd day of September, A. D. 1931.

(Seal)

M. J. Moore,
Acting Commissioner of Patents.
